FLOOR PROTECTION FOR RAILWAY CARS

Karl F. Nystrom, Milwaukee, Wis.

Application December 4, 1941, Serial No. 421,546

3 Claims. (Cl. 105—422)

The invention relates to railway freight cars and has for its object to provide means for protecting the wooden floors now in general use in such equipment, which means will not interfere with the securing of blocking to the wooden flooring.

Another object is to protect the wooden flooring with a metallic sheathing which is perforated so that the car lading may be secured to the flooring through the apertures.

The floors of railway cars are subjected to a great deal of abuse by nails and spikes being driven into them when attaching blocking to them, and also by trucking the lading into the car and by dragging pieces of lading from one part of the car to another. That portion of the car between the opposite side wall doorways is given the most abuse by lading being hauled through the car (by truck or otherwise) to an adjacent car. However, my improved floor protection may be applied over the entire area of the floor if desired.

Another object of the invention is to prevent the curling of the edges of the floor protecting plates. Heavy loads are often hauled into railway cars upon trucks having wheels of small diameter and the pressure of such wheels upon the floor of the car presses the central portions of the protecting plate into the wood floor and causes the edges of the plate to curl upwardly.

Another object of the invention is to provide a floor of which one section is installed as a unit and also removed as a unit when it is necessary to repair it.

Another object is to provide a floor, a part of which is covered by metal protecting plates and another part of which is left uncovered and to design such floor so that the boards comprising the uncovered part may be easily removed and replaced without disturbing, in any way, the protecting plates.

Another object is to provide a floor which is easily assembled. Certain types of floor protecting plates now in service are difficult to apply to the car because it is necessary to make a preliminary application of the plates, then remove such plates, and cut grooves in the floor boards to accommodate the depending flanges of the plates, the location of such grooves being gauged by the position of the plates in the preliminary application. In a floor constructed according to my present invention, the unitary doorway section may first be permanently installed and then the remaining part of the floor, which is comprised

of standard tongue and groove boards, may be sprung into place in the conventional manner.

Other objects and advantages of my invention will be apparent from the following detailed description by referring to the accompanying drawing.

In the drawing:

Fig. 1 is a plan view of a railway car floor embodying my invention.

10 Figs. 2 and 3 are sections on lines 2—2 and 3—3, respectively, of Fig. 1.

Fig. 4 is an enlarged view similar to a portion of Fig. 3 showing the construction at an edge of a floor protecting plate.

15 Fig. 5 is an enlarged view showing abutting edges of adjacent floor protecting plates.

Figs. 1 to 3 show a common floor construction of a railway car comprising the center sill 2; side sills 3; intermediate floor stringers 5; and cross members 6 of the underframe. Members which serve as both threshold plates 8 and floor supports 9 are carried by the side sills 3 at the doorways, the doorways being included between the spaced apart door posts 11 shown in Fig. 1. The side sheathing 12 and side lining 14 are supported by the door posts 11 and the side posts 15. The wooden floor 17 is supported by the floor supports 9, the intermediate floor stringers 5 and the center sill 2.

20 30 As shown in Fig. 1, the floor protector covers the entire floor included between the doorways, and preferably extends beyond the door posts 11 a small distance, such as one foot. The floor protector is preferably comprised of a plurality of metallic plates 20 each extending from side to side of the car and arranged with their adjacent edges formed with abutting depending flanges 21 embedded in transversely extending grooves 23 cut in the upper surface of the wooden floor 17.

40 45 (See Fig. 5.) The plates 20 may be welded (24) together flush with the floor, either intermittently or continuously, or, as has been found preferable to reduce buckling, may be welded (26) at the free ends of the depending flanges 21 before the plates and floor boards are placed together.

The floor plates 20 are securely fastened to the wooden floor boards preferably by the bolts 27 so as to form a unit floor section which may be applied to the car, preferably from the top before the car roof has been applied. Bolts 29 through parts of the car underframe are then applied to hold said section rigidly in position as part of the car floor. The floor plates 20 may be welded (30) 55 to the threshold plates 8 to reinforce the car and

help to hold it square. The floor plates 20 are preferably provided with a plurality of closely spaced apertures 31 so that lading or bracing may be nailed or otherwise secured to the wooden floor 17.

The floor protecting plates 20 which form the marginal parts of the above mentioned unit floor section have formed on their outer edges depending flanges 33 and outstanding reflanges 34. The adjacent uncovered boards 36 are provided with specially formed grooves 37 adapted to receive the reflanges 34. These function both to hold the protecting plates 20 down upon the wooden floor 17 and to form seals to prevent the leakage of grain or other fine commodity. All the other uncovered boards between the floor plate and opposite end walls of the car are preferably standard boards, either tongue and groove, or shiplap, and may be sprung into place in the conventional manner and also removed and replaced without disturbing the protected part of the floor.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a railway car; a floor stringer forming part of the underframe of the car, a floor supported by said stringer and comprising a plurality of wooden boards crossing said stringer, a perforated metallic floor protecting plate having one margin thereof formed with a depending flange 35

extending between two of said boards, said flange formed with an outwardly projecting reflange projecting into a groove in the edge of one of the last mentioned boards, and bolts positioned adjacent said flange which pass through some of said perforations, said floor and said stringer to hold down both of said last mentioned boards.

6 2. In a railway car; a floor comprising a plurality of wooden boards, a perforated metallic floor protecting plate having one margin thereof formed with a depending flange extending between two of said boards, said flange formed with an outwardly projecting reflange projecting into a groove in the edge of one of the last mentioned boards, and bolts positioned adjacent said flange which pass through some of said perforations and said floor to hold down both of said last mentioned boards.

10 3. In a railway car having a floor stringer forming part of the car underframe and a floor structure, said floor including a unit section comprising a plurality of wooden boards crossing said stringer, a perforated metallic floor protecting plate having the opposite margins thereof parallel to said boards formed with depending flanges 20 25 each formed with an outwardly projecting reflange, and bolts passing through some of said perforations and said boards, said floor also including other wooden boards adjacent said opposite margins of the unit section and provided with grooves receiving said outwardly projecting reflanges, said floor structure including other bolts passing through some of said perforations, said boards and said stringer.

K. F. NYSTROM.
